STACCATO TAP

Vincent Sunseri, Tarzana, Calif.

Application May 18, 1948, Serial No. 27,791

3 Claims. (Cl. 36—8.3)

1

This invention relates to taps of the type used by dancers in "tap dancing," and more particularly that type of tap wherein a loose plate or member mounted in a frame or body element is actuated by rhythmic contact with the floor during the act of dancing to produce sharp clicking sounds audibly emphasizing the foot motions of the dancer.

It is desirable that such a tap be free of exposed screw or rivet heads, or other objectionable projecting parts, which might damage the floor or interfere with smooth and rapid foot motions; and that simple and effective provision be made for maintaining the movable element of the tap in sensitive sound-producing relation with the fixed element thereof and in a manner which may be easily assembled while the parts are efficiently locked together against accidental displacement after assembly and especially while in actual use by the dancer.

It is, therefore, an object of the said invention to meet all the desirable conditions of such a device in a simple and efficient manner; and the advantages of my improved construction from both the point of view of manufacture and use will become apparent as the same is further described, by way of example, having reference to the accompanying drawing, wherein:

Figure 1 is a plan of underside of a tap embodying the said invention;

Figure 2 is a cross section of the same taken on a plane indicated by the line 2—2 in Figure 1, the tap being shown as attached to the toe end of the sole of a shoe;

Figure 3 is a rear end elevation of the tap;

Figure 4 is a cross section of the same taken on a plane indicated by the line 4—4 in Figure 1;

Figure 5 is a plan of underside of the fixed body element of the tap;

Figure 6 is a plan of the movable sound-producing element or tongue of the tap;

Figure 7 is a plan of the retainer spring; and

Figure 8 is an elevation of the said spring.

Similar characters of reference indicate similar parts in the several figures of the drawing.

The general shape of the tap is, of course, more or less governed by the general shape of the shoe to which it is intended to be applied and also according to whether it is to be applied to the toe or the heel of the shoe, as will be readily understood. Consequently, the fixed body member 10 is generally of arcuate form and outline, being usually semi-elliptical as illustrated.

I prefer to make this fixed body element 10 of open-center construction so that it is some-

2

what in the form of a horse shoe, as clearly shown in Figure 5, the screw holes 11 being arranged about the inner portion 12 of the said frame and remote from the outer portion or rim 13 thereof.

The movable sounding plate 14 is similar in outline to the body portion 10 but is of smaller overall dimensions so that it may overlap the inner portion 12 of the body element 10 while exposing the outer marginal portion or rim 13 of the said body member. This outer rim 13 projects materially below the perforated portion 12 of the body element and has its inner surface grooved or rabbeted throughout, as at 15, to receive the marginal lip 16 provided on the sounding plate 14.

As the said groove 15 opens rearwardly of the said rim 13, it will be apparent that the marginal lip 16 of the plate 14 may be easily slid forwardly into the said groove until it is engaged throughout its length by the flange 17 of the said body element 10 as clearly shown in Figures 1 to 4 of the drawing.

The height of the said groove 15 is greater than the thickness of the entering lip 16 so that vertical motion of the sounding plate 14 with respect to the body element 10 is permitted; but in its assembled position the said sounding plate 14 is urged downwardly by a leaf spring 18 so that the lip 16 impinges the flange 17 of the body element.

The central portion of this leaf spring 18 is bowed downwardly, as shown, to bear upon the upper surface of the movable plate 14; and this leaf spring extends transversely of the device 35 with its end portions engaged in recesses 19 provided on the underside of the said fixed body element, the upper surface of the movable plate 14 being also transversely recessed as at 20 to receive the medial portion of the said spring 18.

Thus, the said spring 18 performs the dual function of biasing the movable plate 14 against the flange 17 of the fixed body element and of locking the said plate 14 in assembled position in the said body element. Removal of the plate 14 from the body element 10 may only be effected by pressing the end portions of the spring 18, as with the thumbs, downwardly toward the plate 14 and consequently out of engagement with the recesses 19 of the body element, whereupon the plate 14 may be slid rearwardly out of the groove 15 while the ends of the spring are so depressed.

It will be noted, however, that this is practically impossible of accomplishment when the device is once affixed to a shoe and, as the locked plate 14 then conceals the screw heads, the assembly

is quite fool-proof against displacement of the parts.

In assembling the device on a shoe, the body element 10 is simply attached thereto by suitable screws entered through the holes 11 and while the rim side of the body element is presented upwardly, as in Figure 1, the ends of the leaf spring are positioned in the recesses 19 of the element 10 with the bowed center of the spring presented upwardly. The toe end of the plate or tongue 14 is then pressed downwardly on the central portion of the spring to more or less flatten it and thereby permit the marginal lip 16 of the said plate 14 to be moved forwardly and fully into the groove 15 and beneath the flange 17 of the said body member 10; whereupon the central portion of the leaf spring 18 will snap into the transverse groove 20 of the plate 14 and thus lock the said plate in position and against removal from the said groove 15.

In action, the striking of the plate 14 against the floor in the act of dancing causes the plate to move upwardly within the groove 15 so that its lip 16 is separated from the said flange 17 of the body element and driven against the inner portion 12 of the frame 10. This movement, and its recovery during dancing motions, produces the highly desirable tapping or clicking noises in a highly satisfactory manner. I prefer to crown or dish the movable plate downwardly, as clearly seen in Figures 3 and 4, both to centralize the actual contact area of the plate with the floor and also to provide, between the said plate and the shoe, a sound chamber which opens rearwardly of the device as will be observed from an examination of Figure 2.

The simplicity of the parts and method of assembly will be readily apparent, and this is effected in a manner assuring proper relative positioning of these parts and the sensitive biassing of the movable plate while at the same time an extensive area of contact between the lip of the plate and the flange of the body element is provided to assure highly effective sound-producing qualities in the device.

This invention may be developed within the scope of the following claims without departing from the essential features of the said invention, and it is desired that the specification and drawing be read as being merely illustrative of a practical embodiment of the same and not in a strictly limiting sense.

What I claim is:

1. In a tap of the type described, a substantially U-shaped arcuate body element for attachment to a dancing shoe, the inner marginal portion of the said element being perforated to

receive screws or rivets and the outer marginal portion raised to form an arcuate rim, the inner edge of said rim being rabbeted, an impact plate having an edged portion in thinned counterpart of the rabbet of said rim for loose vertical movement therein, said rabbet being arranged to receive said plate by endwise slanting movement of the plate thereinto, and a spring latch concealed behind said plate adapted to engage and lock said plate against removal when said plate is fully entered in the rim of said body element, said latch being further adapted to yieldably press said plate outwardly against said rim.

2. In a tap of the type described, a substantially U-shaped arcuate body element for attachment to a dancing shoe, the inner marginal portion of the said element being perforated to receive screws or rivets and the outer marginal portion raised to form an arcuate rim, the inner edge of said rim being rabbeted, an impact plate having an edged portion in thinned counterpart of the rabbet of said rim for loose vertical movement therein, said rabbet being arranged to receive said plate by endwise slanting movement of the plate thereinto, and a transversely arranged leaf spring latch concealed behind said plate and adapted to engage and lock said plate against removal when said plate is fully entered in the rim of said body element.

3. In a tap of the type described, a substantially U-shaped arcuate body element for attachment to a dancing shoe, the inner marginal portion of the said element being perforated to receive screws or rivets and the outer marginal portion raised to form an arcuate rim, the inner edge of said rim being rabbeted, an impact plate having an edged portion in thinned counterpart of the rabbet of said rim for loose vertical movement therein, said rabbet being arranged to receive said plate by endwise slanting movement of the plate thereinto, the back of said plate being transversely slotted and the opposed face of the inner marginal portion of said element also being transversely slotted, and a transverse spring latch adapted to engage in the slots of said plate and said element when said plate is fully entered in the rim of said body element.
